Specification for Design.

Patented Jan. 1, 1918.

Application filed February 2, 1917. Serial No. 146,284. Term of patent 14 years.

To all whom it may concern:

Be it known that I, HARRY L. JOHNSON, a citizen of the United States, residing at Johnson City, in the county of Broome and State of New York, have invented a new, original, and ornamental Design for Shoe-Soles, of which the following is a specification, reference being had to the accompanying drawing, forming part thereof.

The figure is a plan view of a shoe sole, illustrating my new design. The drawing shows the complete article, and the curved line at the heel end of the sole indicates where a heel would be located.

I claim:

The ornamental design for a shoe sole as shown.

HARRY L. JOHNSON.
